ABSTRACT

A long persistence display screen that can be utilized with any conventional cathode ray tube is disclosed. The long persistence display screen of this invention comprises a translucent or transparent base material such as mylar that has been suitably impregnated with an appropriate phosphor material. This semi-flexible screen is placed in intimate contact with the cathode ray tube with which it is utilized. Any rapidly traced wave form, or the like, illuminated on the cathode ray tube will be visible on the screen of this invention for a longer period of time due to the action of the after-glow in the phosphor used in the screen.

**LONG PERSISTENCE DISPLAY SCREEN
SUPPLEMENT TO CRT**

The invention described herein may be manufactured, used, and licensed by or for the Government for Governmental purposes without the payment to me of any royalties thereon.

BACKGROUND OF THE INVENTION

This invention relates to display screens, and more particularly to long persistence display screens utilized as supplements to a cathode ray tube.

A given display or trace on a conventional cathode ray tube has a short persistence unless, of course, the trace or display is repeated over and over again. It is known in the art that certain phosphors, when excited, exhibit a long persistence and various devices utilizing this fact are known in the art. However, these devices are all specially built to serve a particular need. None of these prior art, specially built devices can be readily used with any conventional cathode ray tube. Thus, a need exists for a device that can be utilized as a supplement to any cathode ray tube to provide a long persistence display.

Such a device can be used to provide a long persistence display with any cathode ray tube either of the lab or TV type and will, of course, have a large number of applications. For example, a long persistence screen designed in accordance with this invention can be used to provide a means for longer term storage of, for example, data transmitted by any conventional means and can be used to provide a means of converting a standard lab oscilloscope to an oscilloscope having a long-term storage capability approaching the display time characteristics of a storage tube display unit. As will be apparent later, there are, of course, many other uses for a long persistence display screen constructed in accordance with this invention.

SUMMARY OF THE INVENTION

The long persistence display screen of this invention comprises a base material such as mylar that has been suitably impregnated with an appropriate phosphor or phosphors, as the case may be. The semi-flexible screen impregnated with the phosphor is placed on the face of a conventional cathode ray tube. Any rapidly traced wave form illuminated on the cathode ray tube will be visible for a longer period of time on the screen of this invention. Since the screen is made of mylar, or the like, it is flexible or at least semi-flexible and therefore can be readily placed on the face of a cathode ray tube. Further, it can be removed and utilized with still another cathode ray tube. Thus, screens constructed in accordance with this invention can be utilized with any cathode ray tube. One merely secures the screen to the face of the cathode ray tube by any suitable means. In fact, the screen itself could be coated with a transparent, tacky material so that it would adhere to the face of the cathode ray tube without any separate securing means. Or, an adhesive could be placed along the border of the screen.

It is therefore an object of this invention to provide a long persistence display screen.

It is another object of this invention to provide a long persistence display screen used as a supplement to a conventional cathode ray tube.

It is still another object of this invention to provide a flexible, long persistence display screen.

It is a further object of this invention to provide a flexible, long persistence display screen that can be utilized with any conventional cathode ray tube.

It is still a further object of this invention to provide a long persistence display screen that can be readily attached to and removed from the face plate of a conventional cathode ray tube.

10 BRIEF DESCRIPTION OF THE DRAWING

The above-mentioned and other objects of the invention will become readily apparent from the following detailed description when read in conjunction with the 15 annexed drawing in which:

FIG. 1 is a pictorial view showing a display screen constructed in accordance with this invention;

FIG. 2 is a cross-sectional view of a display screen constructed in accordance with this invention;

FIG. 3 is a side view of a conventional cathode ray tube showing the screen of this invention in intimate contact with the face plate of the cathode ray tube; and

FIG. 4 is a front view of a cathode ray tube with the screen of this invention in intimate contact with the 25 face plate of the cathode ray tube.

DETAILED DESCRIPTION OF THE INVENTION

FIG. 1 is a pictorial view of the display screen 1 constructed in accordance with this invention. As more 30 clearly shown in FIG. 2, the screen 1 consists of a base material that has been impregnated with a phosphor or phosphors 2.

When screen 1 is excited, phosphor 2 will provide an afterglow in response to the excitation. The length of time that this afterglow persists depends upon the type of phosphor utilized. Thus, by selecting a particular phosphor for phosphor 2 various different phosphorescent times can be obtained. Phosphors, both organic or inorganic, exhibiting a whole range of phosphorescent 35 time in response to excitation are known in the art. For example, the inorganic phosphors are of the Zns, CdS, or ZnS:CdS class activated with Ag, Cu, Mg, Mn, etc. These phosphors provide a phosphorescent lifetime of from a few milliseconds to hours. The organic types usually have conjugated double bonds and closed cyclic ring configurations. The specific or particular phosphor or phosphors used for phosphor 2 is not critical to this invention. Any suitable phosphor or phosphors that provide the desired persistence time can be utilized. It is, of course, true that this invention basically relates to long persistence display screens and therefore only those phosphors that provide sufficiently 45 useable long persistence times would normally be utilized. However, in some cases a persistence of but several milliseconds may be sufficiently long for that particular application. In other words, screens designed in accordance with this invention can be designed to have specific controlled persistence times. The times can range from several milliseconds to hours.

The screen, as shown in FIG. 1, is generally rectangular shaped. The screen can take on any desired shape. Since the screens are intended for use with conventional cathode ray tubes they will be either rectangular shaped or circular since cathode ray tubes are generally either rectangular or circular shaped. It is, of course, true that a circular or rectangular screen of sufficient size can be used with either a circular or rectangular 50 55 60 65

cathode ray tube. Since screen 1 is semi-flexible, it can be made into a continuous sheet rather than an individual screen and the sheet can be cut to any desired size to provide an individual screen from the long sheet. This sheet can be folded or rolled up for convenient storage.

FIG. 3 shows screen 1 as it is utilized with a conventional cathode ray tube 3. As shown in FIG. 3, screen 1 is placed in intimate contact with the face plate 5 of cathode ray tube 3. Screen 1 can be secured to face plate 5 by any suitable means. For example, screen 1 can be taped onto the face plate of cathode ray tube 3, or a border of adhesive can be provided around the edges of screen 1, or screen 1 can have coated thereon a transparent adhesive so that the entire screen will readily adhere to face plate 5. Screen 1 is to be removably secured to face plate 5 so that it can be readily removed from the face plate after use and again utilized with either cathode ray tube 3 or any other cathode ray tube. In other words, it is intended that screen 1 be readily applied to and removed from face plate 5 of cathode ray tube 3. FIG. 4 is merely a front view of cathode ray tube of FIG. 3 and shows screen 1 in intimate contact with face plate 5.

After screen 1 has been secured to face plate 5, any trace that appears across the screen of cathode ray tube 3 will excite the phosphor in screen 1. Therefore, screen 1 will phosphoresce or glow in the excited areas and thereby provide a replica of the trace that appeared across the screen of the cathode ray tube. Since the phosphor used in screen 1 provides a long persistence, the trace of afterglow will remain on screen 1 long after the trace has disappeared on the screen of the cathode ray tube. In this manner, any trace or data can be studied for a period of time longer than that which would be normally provided with the cathode ray tube itself. By placing screen 1 across the face plate of the cathode ray tube, any data will remain for a much longer period of time and can, therefore, be analyzed and studied by the observer. In addition to providing long persistence for data, screen 1 has the capability of providing a means for converting a standard laboratory oscilloscope to an oscilloscope having a long term storage capability approaching that of the display time characteristics of a storage tube display unit. In other words, by means of screen 1, any conventional cathode ray tube can be converted to one having a long term storage capability. Screen 1 can be used with any conventional cathode ray tube and can be readily applied to or removed from the face plate of the cathode ray tube. Thus, this invention provides a long term storage capability with conventional cathode ray tubes that heretofore has not been available in the art.

While the invention has been described with reference to a particular embodiment, it will be obvious to those skilled in the art that various changes and modifications can be made to the embodiment disclosed with-

out departing from the spirit and scope of the invention as set forth in the appended claims.

What is claimed is:

1. A long persistence display screen supplement for a cathode ray tube comprising:

a flexible binder, and

phosphor impregnated into said flexible binder.

2. A long persistence display screen as described in claim 1 wherein said flexible binder is made from a material selected from the family of materials known as silastics.

3. A long persistence display screen as described in claim 1 wherein said flexible binder is mylar.

4. A long persistence display screen as defined in claim 3 wherein said phosphor is ZnS activated with one of the elements selected from the group consisting of Ag, Cu, Mg, and Mn.

5. A long persistence display screen as defined in claim 2 wherein said phosphor is CdS activated by one of the elements selected from the group consisting of Ag, Cu, Mg, and Mn.

6. A long persistence display screen as defined in claim 2 wherein said phosphor is ZnS:CdS activated with one of the elements selected from the group consisting of Ag, Cu, Mg, and Mn.

7. A long persistence display system comprising:
a cathode ray tube; and
a flexible screen comprising a flexible binder impregnated with a long persistence phosphor, said flexible screen being placed directly on the outside of the face plate of said cathode ray tube.

8. A long persistence display system as defined in claim 7 wherein said long persistence phosphor is ZnS activated with one of the elements selected from the group consisting of Ag, Cu, Mg, and Mn.

9. A long persistence display system as defined in claim 7 wherein said long persistence phosphor is CdS activated by one of the elements selected from the group consisting of Ag, Cu, Mg and Mn.

10. A long persistence display system as defined in claim 7 wherein said long persistence phosphor is ZnS:CdS activated with one of the elements selected from the group consisting of Ag, Cu, Mg and Mn.

11. A method for providing a long persistence display with a conventional cathode ray tube having a short persistence time comprising the steps of:

1. placing a flexible long persistence screen directly on the outside of the face plate of a cathode ray tube;

2. providing a trace across the screen of the cathode ray tube;

3. exciting the phosphor of said flexible screen from said trace across the screen of said cathode ray tube to provide a duplicate of said trace; and

4. removing said trace from said cathode ray tube.
